PROCESS FOR REMOVING SULPHUR COM-
POUNDS FROM HYDROCARBONS

Philip J. Wilson, Jr., Joseph H. Wells, and Pauline M. Sommerfeld, Pittsburgh, Pa., assignors to Carnegie-Illinois Steel Corporation, a corporation of New Jersey

No Drawing. Application April 24, 1945,
Serial No. 590,120

8 Claims. (Cl. 202—42)

1

For the production of many chemical products employed in industries such as the explosives and dye industries, there are required large quantities of pure benzene, which forms the starting material for a wide variety of such products. Thus pure benzene is employed in the manufacture of phenol, and in the production of nitrobenzene which may be converted readily into aniline, to mention only a few compounds obtainable from benzene as the starting material, and whose nitration products and derivatives find wide application in the fields of explosives, dye-stuffs, and pharmaceuticals.

The most important source of benzene is the coal tar and light oil produced by the destructive distillation of bituminous coal. This benzene is, in fact, the parent hydrocarbon of all of the aromatic compounds.

The production of pure benzene is rather involved. It will be recalled that not only benzene, but also numerous methylbenzenes, and many more highly condensed aromatic hydrocarbons, such as naphthalene, acenaphthene, anthracene and phenanthrene, fluoranthene, pyrene, chrysene, and innumerable other compounds, are obtained by the dry distillation of coal. They are present in coal tar and light oils which are produced in great quantities in the manufacture of illuminating gas and in the coke industry.

The rapid, well known development of the chemistry of the benzene derivatives is due largely to the fact that the aromatic parent hydrocarbons are present so largely in coal tar and coke oven light oils, and are accessible in large amounts to various technical industries. While in the case of the paraffins, their very nature renders them unsuitable for the preparation of the aromatic bodies, the benzene hydrocarbons, on the other hand, because of the readiness with which they enter into all kinds of reactions, constitute not only the simplest, but the practical foundation for the unbuilding of the chemistry of the aromatic derivatives. Coal tar, and more especially coke oven light oils, which contain these hydrocarbons, are inexhaustible sources for the preparation of benzene and numerous benzene derivatives, many of which are of highest strategic importance militarily, and also constitute the foundation of the dye industry, while also, in many instances, constituting important sources of valuable pharmaceutical products.

Coal tar and coke oven light oils contain not only aromatic hydrocarbons, but also paraffins, thiophene, methylated thiophenes, phenols, pyridine bases, related compounds, and their deriva-

2

tives. Coke oven light oil, which is one of the greatest sources for the recovery of benzene, is usually recovered by scrubbing the coke oven gas with a straw or absorbent oil. The absorbent oil, containing in solution benzene and its homologues, together with lesser amounts of paraffins, thiophene, pyridine, and other compounds, is steam distilled to produce an overhead distillate which is the light oil itself. This is an oil specifically lighter than water and usually boiling up to 160° to 200° C. This light oil or suitable fractions recovered from it by distillation are freed from resins, olefins, pyridine bases, and other unsaturated compounds, by washing with 66° Bé. sulphuric acid in suitable amounts, for instance 5400 pounds of the acids to 5500 gallons of the oil. The acid is drained from the agitator and the acidified oil is neutralized with caustic soda, for instance a twenty per cent caustic soda solution, which both neutralizes residual acid and removes the phenols from the oil.

The thus "sweetened" oil is separated from the aqueous layer and charged to a fractionating still and carefully fractionated, there being recovered products, such as "motor" benzene, "pure" benzene, toluol and xylol of standard quality.

All grades of benzene thus normally recovered contain varying amounts of thiophene and, since the sulphur of the thiophene tends to render explosives produced from the benzene hypersensitive, to interfere with the true shades of dyes produced from the benzene, and to render toxic those pharmaceutical products originating from the benzene, as well as to poison catalysts used in catalytic processes, the complete removal of the varying amounts of thiophene contained in the benzene assumes importance.

Many procedures for removing thiophene from benzene have been proposed. Among such procedures may be mentioned the reaction with aluminum chloride, or by the use of much larger quantities of sulphuric acid of 66° Bé. gravity, or even more concentrated sulphuric acid, or by the use of "oleum" (fuming sulphuric acid). For the present purposes, all prior methods fail because the thiophene either is only partially removed or there is excessive sulphonation of the benzene, or the cost of equipment and maintenance is excessive.

The present process provides a procedure for removing thiophene from benzene either completely, or to an extent wherein any residual thiophene is so small in amount as to be undetectable by the most sensitive reactions therefor.

In accordance with the present invention, the

"motor" benzene, the "pure" benzene, the light oil referred to above herein, or other fractions of the light oil, are treated for the removal of thiophene. The "motor" grade benzene is a grade that is suitable as motor fuel. The "pure" benzene is what is referred to as "industrially pure." Both grades of benzene contain thiophene, the amounts of which depend upon the quality of the coal from which the benzene has been obtained. Thus some of these benzenes and/or light oils are found to contain only from about 0.001 per cent to 0.002 per cent thiophene, while others contain upwards of 0.03 per cent of thiophene, or more. Even such small amounts of thiophene as the 0.001 per cent mentioned above have proved objectionable and have rendered the benzene unacceptable for the purposes indicated above herein.

In accordance with the present invention, thiophene and thiophene compounds are removed from aromatic hydrocarbons by a process that is simple and relatively inexpensive. In the process of the present invention, a solution consisting of an alkali, water, and an alcohol, is added to the hydrocarbon solution, containing thiophene or its homologues, either in the kettle of a still before distillation or at the top of the fractionating column during distillation. On distilling, the major part of the distillate from the top of the column is free from thiophene.

The alkali employed in the present process may be sodium hydroxide or potassium hydroxide and the alcohol may be any aliphatic alcohol as methyl, ethyl, propyl, or the like. It is preferred to use an alcohol boiling below the boiling points of the hydrocarbon and thiophene in any particular case. In addition to the foregoing alcohols, there may be employed also secondary alcohols, such as isopropyl alcohol, or tertiary alcohols, such as tertiary butyl alcohol.

The alkali employed in the present process should be present at least in equimolecular amounts with the thiophene present, although usually a larger amount is preferable, and enough alcohol should be used to carry the aromatic hydrocarbon over in the form of the azeotrope with the alcohol. In case complete removal of thiophene should not be required for a particular application of the benzene, the amount of alcohol added during distillation may be reduced.

The process of the present invention may be carried out in a variety of ways. The two following examples of the procedure are given by way of illustration, as representing two effective modes of operation, although it will be understood that the process is not limited to these specific procedures, as other modifications will become suggested to one skilled in this art. The illustrative examples of the procedure are:

1. The hydrocarbon containing the thiophene is charged into the kettle of a still provided with a fractionating column. As soon as the still is operating uniformly with total reflux, flow of the alkali-water-alcohol solution into the top of the fractionating column is started, so that it runs down countercurrent to the flow of vapors. Distillate can then be taken off the still.

2. The hydrocarbon containing the thiophene is charged into the kettle of the still, together with the alkali-water-alcohol solution and the distillate taken off the top of the fractionating column.

In either case, after a large proportion of the aromatic compound in the feed has been distilled off, a residue in which the thiophene has

been concentrated can be withdrawn from the still.

As a further modification of the process, it may be noted that the process may be carried out by adding the alkali-water-alcohol solution to the thiophene-containing hydrocarbon and refluxing until the distillate from the condenser is free from thiophene, then distilling.

An example is given below to show the results which have been obtained in the application of the present process to the removal of thiophene from nitration grade benzene, together with comparative results obtained by straight fractionation and by azeotropic distillation with methanol.

15 The thiophene concentrations were obtained by a colorimetric method using isatin, which was described by W. L. Glowacki, "The Determination and Examination of Light Oil in Gas," American Gas Association (1941), pages 33 and 34. All the distillations were made in a still equipped with a packed fractionating column. This was equivalent to forty-three theoretical plates measured at total reflux.

In operating the present process, 500 cc. of nitration grade benzene were charged into a still and 138 cc. of sodium hydroxide-water-methanol solution were fed in at the top of the fractionating column during removal of the first 15.8 per cent (by volume) of the benzene as distillate. The said solution contained 5 per cent 25 caustic soda and equal volumes of methanol and water. To the still at the start of the distillation were added 25 cc. of methanol plus 1 cc. of water, and 300 cc. more of methanol were added 30 to the column after 25 per cent by volume of distillate was off.

In the straight fractionation 400 cc. of the benzene were distilled. In the azeotropic distillation with the methanol-water solution, 400 cc. of 40 benzene, 350 cc. of methanol, and 2 cc. of water were charged. The comparative results are indicated in the following table:

Method						
45	Present Improved Process		Straight Fractionation		Azeotropic Distillation with Methanol and Water	
	Distillate, per cent by vol. of charge	Thiophene in Fractions, per cent by wt.	Distillate, per cent by vol. of charge	Thiophene in Fractions, per cent by wt.	Distillate, per cent by vol. of charge	Thiophene in Fractions, per cent by wt.
50	5.8	0	5.2	0.0005	5.3	0
55	10.8	0	11.0	.002	11.9	0
	15.8	0	16.5	.004	18.9	0
	25.0	0	22.0	.005	32.6	0
	35.2	0	32.0	Over .005	39.5	0
	47.2	0	-----	-----	46.5	0.002
	57.2	0	-----	-----	53.4	.001
	70.7	0	-----	-----	60.1	.003
	80.7	0	-----	-----	71.2	.004
	85.7	0	-----	-----	75.9	Over .005
	91.0	Over .005	-----	-----	-----	-----

65 Organic sulphur compounds other than thiophene have been removed or reduced in concentration by use of the present process.

In practicing the present invention, the ratio of water to the alcohol employed can be varied within wide limits, for example from one per cent by volume of water to equal parts of water and alcohol by volume. Where the solution is fed into the top of the fractionating column higher amounts of water in the above-indicated range may be employed, in order to avoid any tendency of the alkali to precipitate out in the column with attendant plugging up of the col-

umn or interference with its efficiency due to such precipitation of the alkali.

We claim:

1. The process of removing thiophene from benzene, which comprises fractionating the benzene in the presence of a caustic soda-methanol-water solution containing the caustic soda in at least equimolecular amounts with the thiophene present in the benzene, the methanol in an amount large enough to carry over the benzene as its azeotrope with the methanol, and the water in an amount from between one per cent by volume of the methanol to substantially equal volume with the methanol.

2. The process of removing thiophene from aromatic hydrocarbons, which comprises fractionating the hydrocarbons in the presence of a potassium hydroxide-methanol-water solution containing the potassium hydroxide in at least equimolecular amounts with the thiophene present in the hydrocarbon, the methanol in an amount large enough to carry over the hydrocarbon as its azeotrope with the methanol, and the water in an amount from between one per cent by volume of the methanol to substantially equal volume with the methanol.

3. The process of removing thiophene from aromatic hydrocarbons, which comprises fractionating the aromatic hydrocarbons in the presence of an alkali-water-alcohol solution containing an alkali of the group consisting of sodium hydroxide and potassium hydroxide in at least equimolecular amounts with the thiophene present in the aromatic hydrocarbons, and enough of an aliphatic alcohol to carry over the aromatic hydrocarbons in the form of its azeotrope with the alcohol, the said alcohol having a boiling point below that of the hydrocarbon to be separated.

4. The process of removing thiophene from aromatic hydrocarbons, which comprises fractionating the aromatic hydrocarbons in the presence of an alkali-water-alcohol solution containing an alkali of the group consisting of sodium hydroxide and potassium hydroxide in at least equimolecular amounts with the thiophene present in the aromatic hydrocarbons, an aliphatic alcohol in an amount large enough to carry over the aromatic hydrocarbons as its azeotrope with the alcohol, the said alcohol having a boiling point below that of the hydrocarbons to be separated, and enough water to maintain the alkali continuously in solution.

5. The process of removing thiophene from aromatic hydrocarbons, which comprises fractionating the aromatic hydrocarbons in the presence of an alkali-water-alcohol solution containing an alkali of the group consisting of sodium hydroxide and potassium hydroxide in at least equi-

molecular amounts with the thiophene present in the aromatic hydrocarbons, an aliphatic alcohol in an amount large enough to carry over the aromatic hydrocarbons as its azeotrope with the alcohol, the said alcohol having a boiling point below that of the aromatic hydrocarbon to be separated, and the water in an amount from between one per cent by volume of the alcohol to substantially equal volume with the alcohol.

10 6. The process of substantially removing thiophene from aromatic hydrocarbons which comprises fractionating the aromatic hydrocarbons in the presence of an alkali-water-alcohol solution containing an alkali of the group consisting of sodium hydroxide and potassium hydroxide in at least equimolecular amounts with the thiophene present in the aromatic hydrocarbons and an aliphatic alcohol having a boiling point below that of the aromatic hydrocarbon to be separated.

15 7. The process of removing organic sulphur compounds present in coal tar and coke oven light oils from aromatic hydrocarbons, which comprises fractionating the hydrocarbon in the presence of an alkali-water-alcohol solution containing an alkali of the group consisting of sodium hydroxide and potassium hydroxide in at least equimolecular amounts with the sulphur compound present in the aromatic hydrocarbon and enough of an aliphatic alcohol to carry over the aromatic hydrocarbon in the form of its azeotrope with the alcohol, said alcohol having a boiling point below that of the hydrocarbon to be separated.

20 8. The process of removing organic sulphur compounds present in coal tar and coke oven light oils from aromatic hydrocarbons which comprises fractionating the hydrocarbons in the presence of an alkali-water-alcohol solution containing an alkali of the group consisting of sodium hydroxide and potassium hydroxide in at least equimolecular amounts with the sulphur compound present in the hydrocarbon, the said alcohol being an aliphatic alcohol having a boiling point below that of the hydrocarbon to be separated.
